UNITED STATES PATENT OFFICE.

AUGUSTIN J. CHEVRETTE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

PICK-CONTROL MECHANISM.

1,280,662.

Specification of Letters Patent. Patented Oct. 8, 1918.

Application filed August 18, 1916. Serial No. 115,610.

To all whom it may concern:

Be it known that I, AUGUSTIN J. CHEVRETTE, a citizen of the United States, residing at Worcester, in the county of Worcester and State of Massachusetts, have invented a new and useful Pick-Control Mechanism, of which the following is a specification.

This invention relates to pick-control mechanism designed for use upon a so-called pick-and-pick loom, in which type of loom drop boxes are provided at each side of the loom and provision is made for picking a shuttle from any one of the boxes on either side of the loom at any beat of the lay. In such looms, through defects in the pattern chains or through mistakes in the manipulation of the loom, it sometimes happens that both boxes which are actively positioned contain shuttles. If either or both of these shuttles is picked under these circumstances a smash inevitably occurs.

It is the principal object of my present invention to prevent such picking of a shuttle when the opposite box is occupied, and also to prevent simultaneous picking of two opposite shuttles. In the attainment of this object I provide mechanism on each side of the loom for controlling the picking devices on the opposite side of the loom, so that the presence of a shuttle in the active box on one side will render the picking devices on the opposite side inoperative.

It is a further object of my invention to control the picking devices directly from the active shuttle boxes, as any less direct system of control introduces possibilities of error in operation. For the attainment of this result in the preferred form of my invention, I provide indicating members operable in conjunction with the shuttle binders of the active shuttle boxes, each of said members being effective to disable the picking device on the opposite side of the loom when the box contains a shuttle.

Further features of my invention relate to improved cam mechanisms for moving the picking devices to operative and inoperative positions, and particularly to cam mechanisms which positively move the picking devices to mid-position on each beat of the lay, from which position they may be thereafter moved to operative or inoperative position according to the indication obtained

from the shuttle binder. By this arrangement the necessary movement of the picking device, after the condition of the shuttle box is indicated, is reduced one half, so that the device will operate at higher speed and over a greater range of box positions.

My invention further relates to certain arrangements and combinations of parts which will be hereinafter described and more particularly pointed out in the appended claims.

A preferred form of my invention is shown in the drawings in which—

Figure 1 is a front elevation of certain parts of a loom with my improved mechanism applied to one side thereof;

Fig. 2 is a top plan view of certain of the parts shown in Fig. 1, as indicated by the arrow 2 in said figure;

Fig. 3 is a sectional elevation taken along the line 3—3 in Fig. 2;

Fig. 4 is a sectional elevation of the actuating cam taken along the line 4—4 in Fig. 2;

Fig. 5 is a front elevation of the indicating member which coöperates with the binders of one set of drop boxes;

Fig. 6 is a vertical sectional view of a set of drop boxes, taken along the line 6—6 in Fig. 7;

Fig. 7 is a horizontal sectional view taken along the line 7—7 in Fig. 6, and

Fig. 8 is a detail view showing the three positions assumed by one of the picking devices.

Referring to the drawings, I have indicated a four-by-four loom, or one in which a set of four drop boxes is provided at each side of the loom. I have shown an indicating member coöperating with the boxes at the left-hand side of the loom and connected to control the picking device at the right-hand side of the loom. It will be understood that this mechanism is duplicated in practice, a similar indicating member coöperating with the drop boxes at the right-hand side and controlling the left-hand picking device. This duplicate mechanism is omitted from the drawings for the sake of clearness.

The usual cam shaft 10 is mounted in 105 bearings in the loom sides 11 and 12, and is provided with a pick roll 13 adapted to co-operate with a pick cam 14 connected

through a pick arm 15 and link 16 to actuate the picker stick 17. In the form shown in the drawings, a single roll 13 is provided to actuate each pick arm 14, and with this arrangement in a pick-and-pick loom the cam shaft makes one complete revolution for each beat of the lay. The roll 13 is mounted upon an arm 18 pivotally connected at 19 to the cam shaft 10. A link 20 is connected at one end to the arm 18 and at its opposite end to a sliding collar 21. The collar 21 is controlled in its longitudinal position on the shaft 10 by a yoke 22 formed on a lever 23 pivoted at 24 and connected by a link 25 to a bell crank 26. The mechanism thus far described is of the usual type and forms no part of my invention. In the operation thereof the bell crank 26 through the lever 23 and yoke 22 slides the 20 collar 21 along the shaft 10, and such movement of the collar rocks the arm 18 on its pivot 19 to move the roll 13 into or out of position for engagement with the pick cam 14.

25 My present invention relates to mechanism for controlling this movement of the pick roll into and out of operative position according to the positions of the shuttles in the boxes. I will first describe the indicating or detecting device through which the indication is obtained. An upright lever 30 (Figs. 5 and 6) is pivoted upon a collar 31 which in turn is pivoted to swing loosely on the end of a shaft 32, acting as a support 35 and forming a swivel mounting for the lever 30. The collar may be positioned on the shaft by a pin 310 (Fig. 6) in the shaft extending into a circumferential slot 311 in the collar. At its upper end the lever 30 is provided with a portion 30^a adapted to engage the swinging outer end of the binder 33 of the actively positioned shuttle box. A spring 34 (Figs. 5 and 7) yieldingly moves the lever so that the portion 30^a is carried 40 to the rear and to the left as viewed in Fig. 5.

In order to give the lever 30 a detecting movement a lever 35 is pivoted by a stud 36 (Fig. 6) on the lay end 37. One portion 50 35^a of the lever 35 engages the lower end of the lever 30, while a portion 35^b extends into the path of a stud 38 fixed to the loom frame 11. At each forward beat of the lay the stud 38 engages the lever 35, swinging the 55 portion 35^a to the left, and thus moving the portion 30^a of the lever 30 to the right beyond the end of the shuttle binder 33. If a shuttle has entered the active shuttle box the corresponding binder will have been 60 pushed forward, the lever 30 will engage the end of the binder as the lay moves back and will thus be held in the position shown in Fig. 5. If the box is empty, however, the portion 30^a will not engage the end of the 65 binder, but will move to the left under the

influence of the spring 34. Such movement occurs as soon as the lay has carried the lever 35 backward away from the stud 38.

A transmitting member 40 is connected to the lower end of the lever 30 and passes 70 around fixed guide pulleys 41, 42 and 43 (Fig. 1), portions of chain or other flexible material being interposed where the member passes around the pulleys. After passing the guide pulley 43 the member 40 is connected to a member 44 having a closed slot 45 formed therein, and having a chain 46 secured to a lug or projection thereon. 75

A stud 47 on the end of an arm 48 projects through the slot 45. The arm 48 is fixed to 80 the end of a vertical shaft 49 secured in bearings 50 supported on the cross-girt 51, forming a portion of the loom frame. At its upper end the shaft 49 (Fig. 2) is provided with an arm 52 having a stud 53 engaging a grooved collar 54 keyed to the cam shaft 10 and slidable thereon. A coil spring 55 encircles the shaft 49 and is secured at one end to the shaft and at the opposite end to one of the bearings 50. This 85 spring tends to move the shaft in the direction of the arrow *a* shown in Fig. 2, thus holding the stud 47 yieldingly against the outer end of the closed slot 45.

The chain 46 passes around a lower fixed 90 guide pulley 60 (Fig. 1) and an upper fixed guide pulley 61 (Fig. 2) and is connected to a swinging arm 63. The arm 63 is pivoted at 64 upon a flange 65 formed on a member 66 pivoted upon a fixed stud 67 100 supported by the cross girt 51. The member 66 is provided with an extension 68 having a pawl 69 formed on the side thereon near its outer end. A spring 70 is secured between the arm 63 and the extension 68, and tends to swing the arm 63 to the left as viewed in Fig. 2.

With these connections it will be seen that when the portion 30^a of the indicating lever is held to the right by engagement with the end of the binder 33 the collar 54 will be held at the left, and the arm 63 will be held at the right in the positions shown in Fig. 2.

I will now describe the mechanism through 110 which these parts control the position of the pick roll 13. A cam 71 (Figs. 1, 2 and 4) is fixed to the cam shaft 10 and rotates in the direction of the arrow *f* in Fig. 4. This cam is provided with an inner groove 72, an outer groove 73 and an intermediate or middle groove 74. These grooves are inter-communicating, and are traversed by a cam roll 75 mounted upon the end of an arm 76 swinging about a fixed pivot 77. The arm 76 is connected by a link 78 to the bell crank 26 (Fig. 1) previously described, and through this connection the cam roll 75 determines the position of the pick roll 13. 120

When the roll 75 is in the inner groove 72 130

the pick roll is in operative position, and when the roll 75 is in the outer groove 73 the roll is inoperative. When the roll 75 is in the intermediate or middle groove 74 the 5 pick roll is in mid-position and requires only a slight movement in one direction or the other to render it operative or inoperative. As the grooves 72 and 73 both communicate at each end with the groove 74 10 the roll is brought back to mid-position during a part of each revolution of the cam, and the picking device is thus advantageously positioned for movement to either of its final positions. The three positions of 15 the picking device and the roll 13 are shown in Fig. 8.

The passage of the roll 75 from the groove 74 to the groove 72 or the groove 73 is determined by a switch 80 mounted on a short 20 shaft 81 having a bearing in the cam 71, and extending beyond the rear face of the cam. A collar 82 is fixed to the shaft 81 and prevents endwise movement of the shaft in its bearing. This collar is shown in 25 dotted lines in Fig. 3, and is provided with a lug 83 coöperating with a spring 84 mounted on the hub of the cam, by which means the switch is retained yieldingly in either position to which it is moved. The collar 30 is secured to the shaft 81 by a screw 85 to which is also secured the end of a chain 86 which passes around a guide pulley 87 mounted on the hub of the cam 71, and extends longitudinally of the cam shaft 10 to 35 an eye 88 carried by the slidable collar 54.

Whenever the collar 54 is moved to the left, the pull upon the chain 86 turns the shaft 81 to carry the switch 80 into the full line position shown in Fig. 4. Such movement of the collar 54 occurs every time the 40 lay moves forward and brings the lever 35 (Fig. 7) into engagement with the fixed stud 38. If the active shuttle box contains a shuttle, the shuttle binder will be pushed 45 forward into the path of the lever 30 and will retain the lever in the position to which it is moved by the lever 35 and stud 38. The collar 54 will thus be held in its left-hand position and the switch 80 will guide 50 the roll 75 into the outer groove 73 of the cam 71, thus rendering the pick roll 13 inoperative. If, however, the active shuttle box is empty, the portion 30' of the lever 30 will move to the left as the lay commences 55 its backward movement. The tension upon the transmitting member 40 will thus be relieved, permitting the spring 55 to move the collar 54 to the right and also permitting the spring 70 to swing the cam arm 60 63 to the left.

The functions of the cam arm 63 and the pawl 69 will now be explained. A collar 90 (Fig. 3) is fixed to the outer end of the short shaft 81 to which the switch 80 is 65 secured. The collar is provided with a tooth

91 positioned for engagement by the pawl 69 on the extension 68 of the member 66. A roll 92 is mounted on a stand 93 secured to the periphery of the cam 71 in position to engage the cam arm 63 when the arm is in 70 its right hand position. When the arm 63 is engaged by the roll 92 it raises the pawl 69 out of the path of the tooth 91, the pawl being thus inoperative. This condition obtains whenever the active shuttle box is occupied and the transmitting member 40 is held under tension by the lever 30. When the box is empty and no tension is applied to the wire or chain 40, the arm 63 swings to the left, and clears the roll 92. The pawl 80 75 85 90 95 100 105 110 115 120 125 130 69 then remains in the path of the tooth 91, engaging the same and thus moving the switch 80 to the dotted line position in Fig. 4. The roll 75 then enters the inner cam groove 72 and the pick roll 13 is moved to operative position.

Briefly summarized, the operation of the mechanism is as follows: At each beat of the lay the lever 30 is operated by the stud 38 to slide the collar 54 to the left and to swing the arm 63 to the right. Such movement of the collar 54 sets the switch 80 in position to render the picking device inoperative. If the shuttle box controlled by the lever 30 is occupied the parts are left in this position and the picking device continues inoperative. If the box is empty the lever 30 swing freely to relieve the tension on the wire 40, the arm 63 moves out of the path of the roll 92, the pawl 69 engages the tooth 91 and turns the switch to its opposite position, and the roll 75 through its connections moves the picking device to operative position. The picking devices on each side of the loom are therefore inoperative whenever the active shuttle box on the opposite side of the loom is occupied. In this way the operations of the picking devices are largely reduced, with a corresponding decrease in wear of parts and power consumed.

The slot 45 (Fig. 1) in the member 44 provides a lost motion connection so that the arm 63 may operate immediately after the lever 30 fails to engage the shuttle binder. The arms 48 and 52, and the collar 54 are of considerable weight, and their inertia might delay the operation of the arm 63 if the lost motion connection were omitted.

Having thus described my invention it will be evident that changes and modifications can be made therein by those skilled in the art without departing from the spirit and scope thereof, as set forth in the claims, and I do not wish to be otherwise limited to the details herein disclosed.

What I claim is:—

1. In a pick-and-pick loom, in combination, a rotating shaft, a picking device

- mounted thereon, means to move said device into and out of operative position, and control mechanism for said means, said means including means to move said picking device positively to mid-position on each beat of the lay, and means to thereafter move said device from mid-position in an indicated direction.
2. In a pick-and-pick loom, in combination, a rotating shaft, a picking device mounted thereon, means to move said device into and out of operative position, and control mechanism for said means, said means including a cam having inner, outer and middle grooves formed therein, a cam follower connected to move said picking device, and a switch controlled by said mechanism to guide said cam follower from said middle groove into a selected groove.
3. In a pick-control mechanism for a pick-and-pick loom, a cam having a plurality of grooves therein, a switch mounted on said cam and movable to either of two positions, means to move said switch positively in one direction at each beat of the lay, and means controlled by the presence or absence of a shuttle in one of the active shuttle boxes for moving said switch in the opposite direction.
4. In a pick-control mechanism for a pick-and-pick loom, a cam having a plurality of grooves therein, a switch mounted on said cam and movable to either of two positions, a collar connected to move with said switch and having a notch, a pawl mounted on a fixed pivot and effective to engage said

notch to turn said collar and switch, and means controlled from one of the active shuttle boxes for moving said pawl into and out of operative position.

5. In a pick-and-pick loom, in combination, a rotating shaft, a picking device mounted thereon, means to move said device to mid-position, and shuttle-controlled means for moving said device therefrom to operative or inoperative position.

6. In a pick-and-pick loom, in combination, a rotating shaft, a picking device mounted thereon, means to move said device to mid-position, and means to move said picking device from mid-position to inoperative position if the active shuttle box on the side of the loom opposite to said picking device contains a shuttle.

7. In a pick-and-pick loom, in combination, a lay, picking mechanism including a pick arm, devices actuated positively and periodically independently of the shuttle to move said pick arm from full operative position on each beat of the lay, a detector effective to determine the presence or absence of a shuttle in the active shuttle box associated with said detector, and means positively actuated independently of the shuttle, controlled by said detector and effective under such control to move said pick arm to operative position when said shuttle box is empty.

In testimony whereof I have hereunto affixed my signature.

AUGUSTIN J. CHEVRETTE.
